B. Wardwell, E. R. Barstow, and
G. C. Hartenfels of Providence, Rhode Island.
Letters Patent. N°. 703. Dated May 8th, 1855.

The Schedule referred to in these Letters Patent & making part of the same.

To all persons to whom these presents shall come.

Be it known that we, Benjamin Wardwell, Ephraim R. Barstow, & George C. Hartenfels, of Providence, in the County of Providence, and State of Rhode Island, have invented a new ornamental design for a Cooking Stove; and we do hereby declare that the same is fully represented in the accompanying drawings of which

Figure 1. denotes a perspective elevation of a Stove constructed with such design. -

Figure 2. is a section of its side plate and oven door.

Figure 3. is a horizontal section of the front plate, & larger front doors.

In Figure 1. A, A, A, are the feet or legs upon which the stove body is supported. B, B, are the base mouldings - C, C, the cornice mouldings such being formed of ovolas, cavettos and fillets as shown in section in Figure 2. These base mouldings are joined to the bottom plate D, while the cornice mouldings are made to project from the top plate E, of the stove. -

The corners of the stove are ornamented as seen at F, F, in figures 1 & 3. - G, is the side plate, and H the front plate, the said side plate being ornamented along its lower and upper edges and made to carry sundry doors as seen at I, K, L, the ornamental character of each of which is exhibited in Figure 1. M, is the hearth plate, while N, O, P, & Q are doors applied to the front plate H.

The ornamental design of each of the doors N, O, is similar to that of the door L, while that of each of the doors P, Q, differs therefrom as seen in figure 1. -

The ornamental design and configuration of the hearth plate as well as that of each of the legs A, is also exhibited in Figure 1. and will clearly be understood by any stove plate pattern maker of skill in his art. The hearth plate carries a slide S, which forms a cover to the chamber below it: neither such slide nor any inscription thereupon entering into or making any part of our design. -

We claim the ornamental design and configuration of the side of the stove, inclusive of its base and cornice mouldings -

And we particularly claim the ornamental design of the larger door I. and that of each of the doors K, L -

We also claim the ornamental design of each door P or Q, that of the hearth plate, and that of each of the legs, the whole being as exhibited in figure 1 -

In testimony whereof we have hereunto set our signatures this Fifteenth day of November A.D. 1854.
